(57) **CLAIM**

I claim the ornamental design for a tailless vane for use in coverings for architectural openings, as shown and described.

DESCRIPTION

FIG. 1 is an isometric view of the present invention; FIG. 2 is a top plan view of the vane of FIG. 1, with a bottom plan view being a mirror image thereof.

FIG. 3 is a front elevation of the vane of FIG. 1, with the rear elevation being identical; and,

FIG. 4 is a right end elevation of the vane of FIG. 1, with the left end elevation being identical.
